UNITED STATES PATENT OFFICE.

HARRY C. HAZARD, OF BALTIMORE, MARYLAND.

ADJUSTABLE FASTENING DEVICE.

1,081,610.

Specification of Letters Patent.

Patented Dec. 16, 1913.

Application filed January 23, 1913. Serial No. 743,869.

To all whom it may concern:

Be it known that I, HARRY C. HAZARD, a citizen of the United States, residing at Baltimore, in the State of Maryland, have invented or discovered certain new and useful Improvements in Adjustable Fastening Devices, of which the following is a specification, reference being had therein to the accompanying drawings.

- 10 This invention has for its object to provide an adjustable fastening device, comprising a looped strip of flexible material, such as a piece of tape, which may be conveniently shortened or lengthened, for the purpose of taking up or letting out a portion of a garment or similar device to which one end of such loop is attached. To this end the bight of the loop is passed around the central bar of a buckle member which is 15 constructed with two slots which form the said central bar and which provide two outside bars. The buckle member thus mounted on the loop coöperates with a second buckle member which is attached to or connected with the garment or similar article at some distance from the point at which the end of the loop is attached to such garment or article. This second buckle member is provided with an opening or slot through which the 20 first-named buckle member, with the bight of the loop, may be passed in such a manner that the said first-named buckle member will overlie the second buckle member so as to enable one limb or ply of the loop to be 25 clamped between the central bar of the first-named buckle member and what may be termed the inner or free bar of the second buckle member; the said second buckle member being attached to or connected with the 30 garment or the like through the medium of an outer bar thereof which may be secured directly to the garment by stitching passing over said outer bar; or may be indirectly attached to such garment by a short loop 35 composed of a strip of fabric and which short loop is attached at one end of the garment with its bight extending around the said outer bar of the second buckle.
- With the adjustable fastening device thus 40 constructed the looped strip of fabric, the bight of which passes around the central bar of the first-named or outer buckle member, may be readily shortened by drawing up its outer ply or limb, and said loop may 45 be lengthened or let out when the said buckle members are slightly loosened or separated from each other.
- By virtue of the construction referred to any portion of a garment to which the adjusting device may be applied may be readily 50 taken up or let out, and will be securely retained in any desired adjustment.
- In the accompanying drawing Figure 1 55 illustrates a portion of a garment, which may be a waist-band or belt, with the improved adjustable fastening device applied thereto, and with the adjustable loop somewhat shortened from its full extent. Fig. 2 is a view illustrative of the manner in which the buckle member on the loop may be 60 passed through the slot of the buckle member attached to the garment. Fig. 3 is an enlarged diagrammatic view to show the manner in which the outer limb or ply of the loop is held in clamped position. Figs. 70 65 and 5 are detail views showing different ways of attaching the second or inner buckle member to the garment.
- Referring to the drawing, 12 denotes a 75 portion of a garment, which may be the 80 waist-band of a pair of drawers, or the like, and 13 is a loop composed of a doubled strip of fabric, such as a piece of tape, both ends of the strip forming the loop being attached at one end 14 of the loop to the garment, 85 by stitching or otherwise. The bight of the loop 13 passes around a central bar 15 of a buckle member 16 provided with two slots 17 and 18, forming inner and outer side 90 bars 19 and 20, so that the said buckle member is slidably mounted on the loop; or so that the loop may, when desired, be pulled through the said slots. Coöperating with the buckle member 16 is a second buckle member 21 preferably constructed with a 95 somewhat wide slot or opening 22 forming what may be termed inner and outer side bars 23 and 24. The inner side bar 23 is free of the garment, so as to enable the buckle member 16 to be readily passed 100 through the opening 22 of the said buckle member 21, and the outer side bar of said buckle member 21 is attached to the garment either directly, as by stitching, as 105 shown in Figs. 1, 2 and 4, or by a short loop 28, as shown in Fig. 5, and one end of which loop is attached to the garment and the bight of which loop passes around the said outer side of the buckle member 21. The buckle member 25, shown in Fig. 4, is pro- 110

vided with an opening 22, through which the buckle member 16, with the bight of the loop 13, may be readily passed, and with a free inner side bar 23, but is provided with 5 a bar 26 slightly separated from the outer side bar 24, which is stitched to the garment, by a slot 27. In all of these different forms of the invention it will be understood that the buckle member 16, with the bight of the 10 loop 13 therein, may be readily passed through a slot or opening 22 of the second buckle member 21 in the manner illustrated in Fig. 2; so that the said buckle member 16 will overlie the buckle member 21 which 15 is attached to the garment, in such a manner that the outer limb or ply of the loop 13 will be clamped between the central bar 15 of the buckle member 16 and the inner or free bar 23 of the underlying buckle member 20 which is attached to or connected with the garment. With the loop thus disposed, when any tension is placed thereon, the said outer ply or limb of the said loop will be securely held in any desired position of adjustment, by being clamped between the 25 central bar 15 of the buckle member 16 and the proximate free inner bar 23 of the underlying buckle member; but the said loop may be readily shortened simply by pulling 30 on the outer ply or limb thereof, and may be again lengthened, when desired, simply by slightly lifting the buckle member 16 away from the underlying buckle member, thus releasing the grip or bind of the two 35 buckle members on the outer limb or ply of said loop 13.

The invention is not to be understood as being limited in its use to any particular form of garment, as the adjustable fastening device may be used with many different garments, as on trousers, belts, or vests, or wherever such an adjustable fastening device of this kind may be deemed desirable.

The invention will be particularly useful 45 in instances where a separable fastening device is desired, as a separation of the parts of this adjustable fastening device may be quickly and easily effected simply by loosening the outer buckle member 16 and passing 50 it, with its bight of the loop 13, inward through the slot or opening 22 of the inner or second buckle member 21. This will be readily understood from Fig. 2 which shows

the parts in the positions they may occupy either in coupling or uncoupling the two 55 buckle members.

Having thus described my invention I claim and desire to secure by Letters Patent:

1. An adjustable fastening device comprising the combination with a garment or article, of a loop formed of a doubled strip of material and both plies of which are attached at one end of said loop to said garment or article, a buckle member mounted 60 on said loop and provided with two slots affording side bars and a central bar around which latter the bight of the loop passes, and a second buckle member secured to the garment or article and provided with a slot 65 or opening through which the first-named buckle member with its bight of fabric may be passed; so that the said first-named buckle member will overlie the said second buckle member in such a manner that the 70 outer limb or ply of the loop may be clamped between proximate bars of said buckle members.

2. An adjustable fastening device comprising the combination with a garment or 80 article, of a loop formed of a doubled strip of material and both plies of which are attached at one end of said loop to said garment or article, a buckle member mounted on said loop and provided with two slots affording side bars and a central bar around 85 which latter the bight of the loop passes, and a second buckle member secured to the garment or article and provided with a slot or opening through which the first-named 90 buckle member with its bight of fabric may be passed; so that the said first-named buckle member will overlie the said second buckle member in such a manner that the outer limb or ply of the loop may be clamped 95 between proximate bars of said buckle members, said second buckle member being directly secured to the garment or article by stitching passing over an outer bar thereof.

In testimony whereof I affix my signature, in presence of two witnesses.

HARRY C. HAZARD.
